HINGED TOP WRINGER

Nicholas L. Etten, Waterloo, Iowa

Application March 25, 1940, Serial No. 325,756

4 Claims. (Cl. 68—263)

This invention relates to wringers and more particularly to a new and improved top head and release mechanism for a wringer.

One of the principal objects of the invention is to provide a wringer of compact design and clean appearance wherein the various necessary mechanical controls are arranged to lie close to the wringer frame in an arrangement both compact and pleasing to the eye.

A further object of the invention is to provide a wringer having a top frame separable from the respective main frames wherein a hinged connection is provided between the top frame and the main frame in order that the action of gravity may cause the top to come to rest on the main frame in proper position, such that the reset lever may be immediately and successfully operated without the necessity of manually manipulating the wringer frame in order to bring the locking elements of the wringer into proper co-operating position.

It is a further object of the invention to provide a wringer having a top frame composed of end sections substantially coextensive with the main frame of the wringer and interconnected by a center portion of reduced cross section, such that a pivoted release bar may be mounted thereover to extend between the end portions of the wringer head to fit substantially flush with the outline of these end portions and follow their general contour to provide a substantially smooth and uninterrupted surface for the wringer top.

Another object of the invention is to provide a wringer reset lever comprising a comparatively short lever adapted to swing in a wide arc about a horizontal plane whereby relatively large mechanical advantage would be obtained by a lever handle positioned at all times closely adjacent the walls of the wringer housing.

Further objects will appear hereinafter.

Referring now more particularly to the drawings:

Fig. 1 is a longitudinal sectional view taken substantially on the center line of a preferred embodiment of the present invention;

Fig. 2 is a detail plan sectional view taken substantially on the plane of the line 2—2 in Fig. 1;

Fig. 3 is a transverse detail sectional view taken substantially on the plane of the line 3—3 in Fig. 1;

Fig. 4 is a fragmental transverse sectional view taken substantially on the plane of the line 4—4 of Fig. 1; and

Fig. 5 is a transverse sectional view taken substantially on the plane of the line 5—5 of Fig. 1.

In the prior art it has been common practice to provide wringers including a frame, a top head, and locking members, as for example, a rotatable shaft having locking portions therein in order to firmly lock a top head in operating position on

the frame. It has been necessary, however, after the emergency release has been actuated to manually position the top head on the wringer and guide the co-operating parts with the locking mechanism into proper spaced relationship in order that the operation of the reset lever will be effective to cause these parts to properly interlock. In the present invention this difficulty is overcome by the provision of a pair of hinges on the wringer top arranged at each end of the wringer in order that the forces of gravity acting on the wringer head will cause it to swing about these hinges and come into proper position so that the operation of the reset lever may lock the top head to the frame.

It has also been quite customary in the prior art to provide manually operable wringer release bars arranged to extend along the wringer rolls in order to provide a convenient means for actuating the pressure sustaining latch of the wringer. So far as is known to the applicant, however, these release bars have invariably taken the form of appendages or projections on the outside of the wringer frame or top head and have never been arranged to follow the contour of the wringer in such a manner as to provide a substantially uninterrupted top frame surface. This result is highly desirable from the standpoint of the attractive commercial design that has been

accomplished in the present invention by the provision of a reduced center portion of the wringer top head so arranged that the release bar may be mounted thereover and shaped to provide an uninterrupted, smooth top surface of the wringer head.

The main frame 10 of the wringer may be constructed in any way customarily used in the art but in the particular structure illustrated it comprises an integral die-casting including a longitudinally extending portion 12 and vertical extending bearing slideways 13 and 14 at each end thereof. The entire frame 10 is mounted on a gear housing or power head 15 which is of similar die-cast construction and which includes a gear chamber 16 closed by a face plate 17 and a mounting sleeve 18 by which the entire wringer structure may be telescoped onto the wringer drive column of a washing machine. Such a washing machine drive column includes a driving shaft 21 which may be coupled to the vertical drive shaft 21 of the wringer by any coupling mechanism, not illustrated, of any of the types customarily used in the art.

The drive shaft 21 is journaled in bearings 22 and 23 at its upper and lower ends respectively and is restrained against upward movement by the top wall of the bearing 22 and restrained against downward movement by the cross pin 24 and washer 25. A pair of driving pinions 26 and 27 are positioned on the shaft

21 and arranged for free longitudinal and rotational movement with respect thereto. These pinions 26 and 27 comprise forward and reverse driving elements for the wringing rolls and are arranged to be driven from the shaft 21 whenever the pinions are moved longitudinally along the shaft sufficiently so that the projections 31 on the gear 26 will be engaged by the cross pin 32 or so that the projections 33 on the pinion 27 will be engaged by the cross pin 34 carried on the shaft 21.

The longitudinal movement of the pinions 26 and 27 is accomplished by means of a shifting yoke 35 extending between the two pinions and adapted to ride in annular grooves 36 cut in the toothed faces of each. A central opening in the shifting gear 35 is mounted on an eccentric pin 37 carried by the stub crank shaft 38 on which the manual control arm 39 is mounted. This general type of mechanism is well understood in the art, it being believed sufficient to point out that by the manipulation of the handle 39 the pinions 26 and 27 will be shifted longitudinally from the neutral central position illustrated to either a forward or reverse driving position wherein one of the pinions will be driven by one of the cross pins 32 or 34 and the driving force thus imparted to the pinion will be transmitted from the pinion teeth to the meshing gear 41. The gear 41 is at all times in mesh with both pinions but whenever one of the pinions is driving, the other pinion is absolutely free with respect to the shaft 21 and may idle in an opposite direction. The gear 41 is carried by a stub shaft 42 extending through a bearing 43 in the face plate 17 and interconnecting the gear 41 with a spur gear 44 which in turn meshes with a spur gear 45 affixed to the extreme end of the shaft 46 on which the upper roll 47 is mounted.

The lower roll 48 includes a shaft 49 mounted at each end in identical bearings 51 carried by the channel-shaped transverse supports 52. These supports 52 are arranged to exert a resilient upward pressure on the bearings 51 and thus maintain sufficient operating pressure between the upper wringer roll 47 and the lower wringer roll 48. To this end members 52 are mounted on the lower ends of a pair of spring pilot bolts 53 which extend upwardly through the roll supporting shoulders or shelves 54. The arrangement is such that the channel members 52 are each suspended between two of the bolts 53 and are urged upwardly against the lower surface of the bearings 51 by the two coiled compression springs 55 telescoped on the bolts 53 and arranged to seat on the upper surfaces of the shelves 54 and act upwardly against the hexagonal head portions of the bolts 53. The upper roll 47 has its shaft 46 journaled in a pair of bearings 48 and 49 each solidly mounted on a pair of oppositely disposed lugs 51 formed integrally with the top frame or head 52 of the wringer.

A longitudinally extending shaft 54 is rotatably mounted in bearings 55 in the top head 52 and is cut away at short portions adjacent each end of the shaft, as shown at 56, to provide semi-cylindrical locking sections 57 adapted to engage with and lock against locking plates 58 provided adjacent each end of the wringer rolls and secured to the lower frame 10 by a plurality of machine screws 59. It is considered desirable to be able to rotate this shaft 54 by the actuation of a short lever arranged to swing in a wide arc and to remain close to the wringer frame at

5 all times and to this end a bevel gear 61 is pinned to the extreme end of the shaft 54 and is positioned to mesh with a similar bevel gear 62 pinned to a vertical stub shaft 63 journaled at its upper end in a bearing 64 provided in a wringer top head casting and supported at its lower end by a bearing 65 in a removable plate 66 secured to the top head casting 52 by a plurality of machine screws 67. The stub shaft 63 is riveted to a circular plate 68 on which a ball shaped resetting handle 69 is secured. By reference to Fig. 2 it will be seen that to rotate the shaft 54 from its released position to the locked position illustrated in Figs. 2 and 3, the ball handle 69 should be moved from the dotted line position illustrated in Fig. 2 through an arc of about 180° to the full line position. It will be appreciated that this arrangement provides a large leverage notwithstanding the fact that the ball handle 69 remains closely adjacent the wringer frame at all times.

The circular plate 68 is provided with a latch notch 70 positioned to move into latching engagement with the pivoted latch member 71 as the ball handle 69 reaches the full line position illustrated. The latch member 71 is a general U-shaped structure and includes a pair of similar side plates 72 by which the latch is pivotally mounted on a pair of trunnions 73, each riveted in an upturned ear portion 74 of the plate 66. A coiled wire spring 75 is mounted on these trunnions 73 and arranged to bear against the latch 71 and to be anchored by a lip 76 struck from the plate 66. The arrangement is such as to cause the latch 71 to tend to pivot in a counter-clockwise direction as viewed in Fig. 1 and thus cause the latch 71 to snap into the latching notch 70 when the ball handle 69 reaches its full line position and retain the plate 68 and the locking shaft 54 in locked engagement until the latch 71 is released.

One of the objects of this invention is to provide a release bar contiguous with the top surface of the upper frame or top head of the wringer. To this end the top head 52 is provided with a central section 78 of greatly reduced cross section extending approximately the length of the wringer rolls and positioned directly above these rolls. It will be seen from examination of Figs. 1, 2, and 4 that this reduced center section 78 takes the form of an inverted U having its top surface 79 at a level considerably lower than the top surface of the end portions 81 and 82 of the wringer top head. This arrangement provides oppositely disposed faces 83 and 84 spaced apart from each other approximately the length of the wringer rolls. The release bar 85 is formed of such length as to fit closely between these oppositely disposed faces and is shaped so that the upper surface of the release bar corresponds in shape to the contour of the end portions 81 and 82 of the wringer. A pivotal mounting for the release bar 85 is provided by forming a pair of openings 86 at each end of the bar 85 and inserting a spring pressed pin 87 within the opening, this pin 87 being formed to include a reduced outer end portion adapted to snap into position and seat in one of the perforations 88 in the faces 83 and 84 of the top frame 52.

To assemble the structure it is only necessary to seat the pins 87 in the openings 86 and then position the release bar 85 in registry with the openings 88 so that the pressure of the springs 86 may snap the pins 87 outwardly and establish pivotal connection at each end of the bar 85.

The bar 85 is operatively connected with the latch 71 by a pair of latch levers 91 extending through the flat face 84 to a position adjacent the latch side plates 72 and mounted on the trunnions 92 secured to the inner surface of the top frame by a plurality of machine screws 93. The end portions 94 of each of these levers extend through openings 95 in the end wall 84 of the end portion of the wringer head and each is arranged to assume a position directly below a flat operating surface 96 formed on the release bar 85 (see Fig. 4). The opposite end of each of the levers 91 is provided with a riveted pin 97 which extends inwardly through elongated slots 98 in the opposed side walls 72 of the latch member 71.

To operate the release mechanism the operator may strike either of the sides of the release bar 85 in such a manner as to cause the bar 85 to pivot about the pins 87 as from the solid line position, as illustrated in Fig. 4, to the dotted line position shown. This pivotal movement in either direction will cause one of the flat surfaces 96 to bear downwardly against the end portion 94 of one of the latch levers 91, thereby pivoting the latch lever 91 about the trunnion 92 and causing the pin 97 to move upwardly and pivot the latch 71 in a clockwise direction about the trunnions 73. This pivotal movement of the latch will release the circular plate 68 and, consequently, leave the locking shaft 54 free for rotation. With the latch released the upward force of the springs 55 will cause the wringer top 52 to swing angularly upwardly around the hinged pins 102. This motion will result in rotary movement of the shaft 54 until the vertical semi-cylindrical locking portions 57 clear the hooked portions of the plates 58, and since the shaft 54 is geared to the stub shaft 63 by the bevel gears 61 and 62, the rotary motion of the shaft will be transmitted to the plate 68 and will swing the knob 69 to its dotted line position. In this connection it will be seen that the hooked portion of each of the plates 58 is so placed and so arranged with respect to the semi-cylindrical portion 57 of the shaft 54 that the force exerted by the coiled pressure springs 55 and transmitted therefrom through the pilot bolts 53, transverse members 52, the bearing blocks 51, the lower roll 48, and the upper roll 47 will act on the top frame 52, causing the locking portions 57 to release from the plates 58 and permitting the entire top head 52 to swing upwardly about a pair of hinges 101 and 102 provided adjacent each end of the top head 52 and joining the top head 52 and the main frame 10.

The hinges 101 and 102 thus permit a complete release of the pressure between the rolls and a complete separation of the top head 52 from the main frame 10, but when this has been accomplished the forces of gravity will act to bring the top head 52 downwardly and the hinges 101 and 102 will at this time guide the top head so that the semi-cylindrical locking portions 57 of the shaft 54 come into exact predetermined position with respect to the upper hooked portions of the plates 58 in order that these parts may properly engage when the ball shaped resetting lever 69 is operated. Thus, it is unnecessary for the operator to grasp the top head of the wringer and manipulate it in any way to bring the locking elements 57 and 58 into adjacent positions. In fact, it is only necessary to swing the lever 69 from its dotted line position to its full line position. This

action, of course, will cause the bevel gears 71 and the locking shaft 54 to rotate and as this locking shaft reaches its locked position the spring 75 will cause the latch 71 to engage the latching notch 70 and restrain the several parts against releasing movement until such time as the release bar 85 is again operated.

While I have shown and described the preferred embodiment of the invention in compliance with the patent statutes, it is subject to numerous modifications and alterations without departing from the invention spirit and I therefore wish to be limited only by the scope of the appended claims.

15. I claim:

1. In a wringer including a frame, a spring, and a pair of pressure rolls, the combination of a top head, a reset shaft extending longitudinally of said head and provided with semi-cylindrical locking sections, hook members stationarily attached to the frame, hinge means interconnecting said frame and said top head and adapted to guide the locking sections of said reset shaft into close relationship with said hook members, means to rotate said reset shaft toward a locked position, a latch for said shaft, and a manually operable release for said latch.

2. In a wringer including a frame, a spring, and a pair of pressure rolls, the combination of a top head, a reset shaft extending longitudinally of said head and provided with semi-cylindrical locking sections, hook members stationarily attached to the frame, hinge means interconnecting said frame and said top head and adapted to guide the locking sections of said reset shaft into close relationship with said hook members, a stub shaft, a bevel gear connection between said reset shaft and said stub shaft, a short reset lever mounted on said stub shaft and adapted to swing in a wide angle, and a manually releasable latch for said lever.

3. In a wringer including a frame, a spring, and a pair of pressure rolls, the combination of a top head, a reset shaft extending longitudinally of said head and provided with semi-cylindrical locking sections, hook members stationarily attached to the frame, hinge means interconnecting said frame and said top head and adapted to guide the locking sections of said reset shaft into close relationship with said hook members, means to rotate said reset shaft toward a locked position, a latch for said shaft, and a manually operable release for said latch, said release mechanism including a release bar pivotally mounted between two end portions of the top head and shaped to follow the general contour of these portions.

4. In a wringer including a frame, a spring, and a pair of pressure rolls, the combination of a top head having end portions substantially coextensive with said frame and a central portion of diminished cross section, said top head being of unitary construction and shaped to provide oppositely disposed faces on the end sections at each end of the diminished center portion; a release bar over said center portion shaped to fit closely adjacent said faces, registering openings in each of said opposite faces, openings in each end of said release bar adapted to register with said first mentioned openings, and spring urged pivot pins to establish pivotal connection between the top head and the release bar when said openings move to positions of registry.

NICHOLAS L. ETTER.
